LE ROY C. MORRIS, OF WATERLOO, IOWA

REVERSIBLE CURRENT HEATING APPARATUS

Application filed April 4, 1930. Serial No. 441,626.

My invention relates to improvements in air circulators, and the object of my improvement is to provide for motor cars or other inclosures, apparatus operative to circulate a current of either warm or unwarmed air therethrough.

Another object of my improvement is to render said apparatus reversible in action to permit the air current to be directed into different places in the inclosure primarily, and for the greater convenience and comfort of an occupant as desired.

Another object of my improvement is to supply valvular means in the apparatus which will be effective in practice to produce the last mentioned object, but will also be operable to shut off the connection between said different places in the inclosure, while at the same time allowing an air current to be driven through the inclosure from one of said places or vents only in the creation of a regular and sustained air circulation through the inclosure and said apparatus.

Other objects will be described specifically hereinafter and defined in the appended claims.

I have accomplished the said objects by the means which are hereinafter described and claimed, and which are illustrated in the accompanying drawings, in which Fig. 1 is a diagrammatic view in side elevation of a motor car, with parts in longitudinal vertical section, removed or broken away, and showing my improved apparatus associated operatively therewith. Fig. 2 is an enlarged front elevation of the valve chamber with the rotary blower removed. Fig. 3 is a like view of the valve chamber with its front wall removed. Fig. 4 is a top plan view of the valve chamber with the blower associated therewith, having a part of the chamber broken away, and Fig. 5 is a central vertical longitudinal section of the heater casing with other elements in elevation, and on another enlarged scale than said Figs. 2 to 4 inclusive.

While my apparatus is shown as associated with a motor car for the creation of a constant air circulation throughout the interior of its body, yet in principle the apparatus may, with necessary modifications in details, be

adapted for an air circulation means for any inclosure, such as an apartment in a dwelling or other structure.

The numeral 43 denotes the motor of a car, having the usual exhaust pipe 44 or manifold with the communicating vent tube 37 which is bent downwardly and carried thence longitudinally below the floor 33 of the car body to the rear to a muffler. Fig. 1 shows the body so seated as to have forward and rear spaced cross seats. In their interspaces and immediately to the rear of the dashboard in the front interspace and the front seat in the rear interspace of the seats, the floor has apertures covered by a guard grating or apertured cover 35 and 23 respectively of like shape, designed to open at the sides to either draw air thereinto from the floor level, or to vent air therealong, as the case may be when the apparatus is differently adjusted.

The numeral 41 denotes a hollow cylindrical casing, preferably as shown in Fig. 5, shaped from a metal sheet formed into a cylinder and having its longitudinal edges crimped for union at 42, the casing being initially mounted in spaced relation concentrically about the exhaust pipe 37 below the floor 33 and intermediate the said floor apertures. The cylinder 41 has cup-shaped end caps 38 made up of mating halves with flanges 39 at the bottom secured removably together, and at the tops by screws or bolts to the entrant end parts of the cylinder, the caps having central sleeves fitting upon the exhaust pipe. The caps have erect tubular seats 40 to receive the lower ends of flexible hose sections 36 and 34 at front and rear, the section 36 delivering to the apertured guard grating 35 in front of the front seat and preferably to the right hand of the steering wheel, and the other section 34 being in communication with a sleeved port 9 in the lower part of a valve-chamber 1 immediately below the floor aperture which is beneath the rear guard member 23, said valve chamber having a pair of open top conduits 6 and 7 which enter the rear floor aperture to be flush with the upper end thereof. Said casing is thus readily assembled or removed.

The valve chamber 1 as shown is rectangular

lar in shape, closed at the bottom by a plate 2, the lower space therein in communication with the sleeved port 9 serving as a by-pass 8 for compartments 4 and 5 thereabove defined medially by a vertical partition 11, the chamber being closed at the top between the conduits 6 and 7 by a removable top flanged closure plate 10.

The compartments 4 and 5 are always in direct communication with said top conduits 6 and 7. These compartments contain the flanged valves 15 and 19 respectively, which have semicircular front flange recesses 16 and 20 to register with the lower parts of the pair of front wall circular apertures 12 and 13 occasionally, and with the nozzles 29 and 30 respectively secured in communication with said apertures by the headless screws 31 mounted in threaded holes in the rear wall part of a fan-wheel chamber 25 having an operating electric motor 24, said screws entering threaded holes 14 in the front wall of the valve chamber. The motor has the usual pair of conductors 26 and 27 leading to the terminals of a battery or other source of electric current 28. Said valves have respectively like erect fixed central operating rods 17 and 21 terminating at their upper ends in finger buttons 18 and 22 respectively, and the valves may be pushed up or down independently manually and slidably in the compartments 4 and 5 to control the communications between the by-pass 8 and the compartments and conduits 6 and 7, as also the communications of both with the fan-wheel chamber 25.

In cold weather the exhaust pipe 37 being highly heated, may warm the air in the casing 41 passing therethrough in either of opposite directions to enter the body of the car by either the front conduit 36 or between the front and rear seats by the rear conduit 34, according to the adjustments relatively of the valves 15 and 19 in the valve chamber 1. The motor being started to rotate the fan in the housing 25, and the valves set as in Fig. 3, air is drawn from between the seats and the grating 23 downwardly by way of the conduit 6, compartment 4, front port 12, fan-housing 25, and propelled through front port 13, by-pass 8, conduit 34, casing 41 to be there heated, and thence delivered through the conduit 36 to the front grating 35. When the positions of said valves are reversed, the air is reversely directed to deliver warmed air into the rear grating 23, and in both cases a circulation in the car is set up between said gratings. In warm weather, both valves may be pushed down together, thus shutting off the by-pass 8 and casing 41, and then the fan-wheel drives air from one conduit 6 to the other, creating a cool air circulation in the car at the grating 23, but which is forced throughout the car. Three adjustments are thus effected for the convenience of the users.

Having described my invention, what I

claim as new, and desire to secure by Letters Patent, is:

1. In a device of the character described, a blower, a valve-chamber in communication with the inlet- and outlet-ports of the blower, said chamber having conduits leading into spaced parts of an inclosure and containing valves intermediate said conduits movable to control the communications between said inlet- and outlet-ports with the conduits to permit reversal of an air current caused by said blower from one conduit to the other, said valves when both moved in the same and one direction only operating to cut off the communication of the valve-chamber with one conduit while permitting the blower to create a circulation of air through the chamber and said inclosure by way of certain conduits of said chamber only, which lead into one part of the inclosure. 70

2. In a device of the character described, a blower, a valve-chamber in communication with the inlet- and outlet-ports of the blower, said chamber having at one end a conduit, means within said conduit for heating an air current traversing it, said chamber also having at an opposite end a separated pair of conduits leading into an inclosure, the first-mentioned conduit leading into a spaced part of the inclosure, and said chamber containing valves intermediate said first-mentioned conduit and said pair of conduits movable to control the communications between the blower and both sets of conduits to reverse the direction of an air current in said chamber between 90 said sets, said valves being also movable together in one direction only to thus cut off the communication of the chamber and blower with the first-mentioned conduit, while permitting the blower to create an air circulation through said chamber and through said inclosure by way of said pair of conduits. 100

3. In a device of the character described, a valve-chamber having a pair of like compartments opening at one end thereof into an inclosure, the opposite end of the chamber being closed and containing a by-pass for occasional separate communications with the other ends of said compartments, independently operable valves mounted reciprocatingly in said compartments, said chamber having ports opening into said compartments, a blower having communication with said ports, said valves controlling the communications between said blower, said compartments and said by-pass, and a conduit in communication between said by-pass and another part of said inclosure. 110

4. In a device of the character described, a valve-chamber having a pair of compartments opening at one end thereof into an inclosure, the opposite end of the chamber being closed and containing a by-pass for occasional separate communications with the other ends of said compartments, 120

independently operable valves mounted reciprocatingly in said compartments, said chamber having ports opening into said compartments, a blower having communication with said ports, said valves being independently movable to reversibly control the communications between said blower, said compartments and said by-pass, a conduit in communication between said by-pass and another part of said inclosure, and said valves when reciprocated together in one direction closing the communication of the valve-chamber with the last-mentioned conduit while causing the blower to create an air circulation in said inclosure from one of the first-mentioned open ends of the chamber to the other.

5. In a device of the character described, a valve-chamber having a pair of compartments opening at one end thereof into an inclosure, the opposite end of the chamber being closed and containing a by-pass for occasional separate communications with the other ends of said compartments, independently operable valves mounted reciprocatingly in said compartments, said chamber having ports opening into said compartments, a blower having communication with said ports, said valves being independently movable to reversibly control the communications between the blower, said compartments and said by-pass, a closed end casing mounted imperviously at its ends around and intermediately spaced from a traversing pipe for carrying a heated fluid current, and means of communication between opposite parts of said casing and said by-pass, and with another part of said inclosure respectively.

6. In a device of the character described, a valve-chamber having a pair of compartments opening at one end thereof into an inclosure, the opposite end of the chamber being closed and containing a by-pass for occasional separate communications with the other ends of said compartments, said chamber having ports opening into the compartments, a blower communicating with said ports, apertured closures for said ports movable to reverse the communications between the blower, the compartments and by-pass, and movable both in one direction to cut off the by-pass, and a casing for heating means in communication with said by-pass and inclosure.

In testimony whereof I affix my signature.

LE ROY C. MORRIS.
